United States Patent Office

Des. 203,196
Patented Dec. 14, 1965

203,196

DRAWING DESK

Peter P. Druskis, 3100 Canterbury Road,
Bay City, Mich.

Filed Nov. 4, 1964, Ser. No. 82,472

Term of patent 14 years

(Cl. D33—7)

Fig. 2

Fig. 1

FIG. 1 is a front elevational view of a drawing desk showing my new design.

FIG. 2 is a top plan view with the drawing board in lowered position, and the service trays pivoted to open position.

FIG. 3 is an end elevational view with the drawing board in raised position.

FIG. 4 is a rear elevational view.

The end not shown is exactly the same in appearance as the end shown in FIG. 3.

I claim:

The ornamental design for a drawing desk, substantially
